(57) **CLAIM**

The ornamental design for a power over ethernet modem as shown and described.

DESCRIPTION

FIG. 1 is a front-top perspective view of the power over ethernet modem.

FIG. 2 is a back-bottom perspective view of the power over ethernet modem.

FIG. 3 is a top view of the power over ethernet modem.

FIG. 4 is a bottom view of the power over ethernet modem.

FIG. 5 is a right view of the power over ethernet modem.

FIG. 6 is a left view of the power over ethernet modem.

FIG. 7 is a front view of the power over ethernet modem; and,

FIG. 8 is a back view of the power over ethernet modem. The broken lines shown in FIGS. 1-8 represent portions of the power over ethernet modem that form no part of the claim.
